UNITED STATES PATENT OFFICE

96,562

DESIGN FOR A ROOM THERMOSTAT COVER

Lewis J. Schanz, Chicago, Ill., assignor to Ira E. McCabe, Chicago, Ill.

Application January 22, 1935, Serial No. 54,988

Term of patent 14 years

To all whom it may concern:

Be it known that I, Lewis J. Schanz, a citizen of the United States, residing at Chicago, in the county of Cook, State of Illinois, have invented a new, original, and ornamental Design for Room Thermostat Cover, of which the following is a specification, reference being had to the accompanying drawing, forming part thereof.

In the drawing, the figure is a perspective view of a room thermostat cover embodying my design.

The ornamentation on the right side is identical with that shown on the left side of the thermostat cover.

I claim:

The ornamental design for a room thermostat cover substantially as shown and described.

In witness whereof, I hereunto subscribe my name.

LEWIS J. SCHANZ.
